UNITED STATES PATENT OFFICE

107,444

DESIGN FOR A FOOD CONVEYER

Harold J. O'Brien, Toledo, Ohio, assignor to The Swartzbaugh Manufacturing Company, Toledo, Ohio, a corporation of Ohio

Application April 8, 1937, Serial No. 68,634

Term of patent 14 years

To all whom it may concern:

Be it known that I, Harold J. O'Brien, a citizen of the United States and resident of Toledo, in the county of Lucas and State of Ohio, have invented a new, original, and ornamental Design for a Food Conveyer, of which the following is a specification, reference being had to the accompanying drawing forming a part thereof.

Fig. 1 is a perspective view of a food conveyer showing my new design with certain parts in open usable position; Fig. 2 is a similar view thereof, and Fig. 3 is an end view thereof.

The dominant feature of the herein design for a food conveyer, consists in the provision of a substantially rectangular body having its vertical corners rounded from top to bottom so as to substantially merge into the side and end walls thereof and said body being surrounded adjacent its lower edge by a spaced bumper, as shown.

I claim:

The ornamental design for a food conveyer, substantially as shown, and described.

HAROLD J. O'BRIEN.
